UNITED STATES PATENT OFFICE.

MYRON E. KENNEY, OF EVERETT, WASHINGTON, ASSIGNOR OF ONE-SIXTH TO W. H. CARSTENS, OF SEATTLE, WASHINGTON.

SUGAR-SERVING DEVICE.

Application filed May 19, 1926. Serial No. 110,180.

This invention relates to improvements in sugar serving devices and more particularly to a device for dispensing cube or lump sugar; it being the principal object of the invention to provide a container in which a quantity of lump sugar may be contained in a clean and sanitary manner and which is equipped with mechanism whereby the lumps may be dispensed without necessitating one's reaching into or uncovering the container.

More specifically stated, the object of the invention resides in the provision of a sugar dispensing device embodying a base on which the sugar container is mounted and which has a laterally extended portion forming a basin into which the sugar is delivered; the container being equipped with a cover that may be removed for filling and having a trip lever mounted at one side of the container that may be depressed to effect actuation of certain mechanism within the container whereby from one to three cubes of sugar will be delivered into the basin.

Other objects reside in the various details of construction and combination of parts as will hereinafter be described.

In accomplishing these objects, I have provided the improved details of construction, the preferred forms of which are illustrated in the accompanyings, wherein—

Figure 1 is a perspective view of a sugar dispensing device embodied by the present invention.

Figure 2 is a vertical section centrally of the device showing the inclined support on which the sugar is supported, the hand actuated trip and the sugar catch basin formed integral with the base.

Figure 3 is a vertical section taken on the line 3—3 in Figure 2, showing the plates fixed to the trip shaft operating through slots in the inclined sugar supporting plate.

Figure 4 is a horizontal section taken on line 4—4 in Figure 2.

Referring more in detail to the several views of the drawing—

1 designates the base of the device which may be of cast or pressed metal, which provides a mounting and also serves as a closure for the lower end of a vertically disposed, cylindrical housing 2; this housing being seated within an annular flange 3 formed on the base plate and has projecting ears 4

extended through the base and clinched so as to securely attach the housing thereto.

At one side and adjacent the lower edge of the housing 2 is an opening 5 and leading thereto is an inclined chute 6 through which the lumps or cubes of sugar are delivered, by means presently described, into a catch basin 7 which is formed as an integral part of the base plate.

Fitted securely within the upper end of the housing 2, which is of metal, is a continuing, cylindrical housing 8 of glass through which the contents of the device may be discerned and fitted removably over the upper end of the glass housing is a cover 9 which has a small top opening 10 normally closed by a spring retained closure 11, as shown in Figure 3.

Fixed within the lower casing 2 is a sugar supporting plate 15. This is inclined downwardly toward that side of the casing containing the discharge opening 5 and is provided at a point directly above the chute 6 with an opening 16, as shown in Figures 2 and 4, through which the sugar lumps are discharged into the chute. The opening 16 is normally closed by a trap door 17 that is swingingly supported by a pair of parallel, vertically disposed plates 18 mounted on a shaft 19 that extends revolvably through the housing 2 beneath the inclined plate 15 and which at one end outside of the casing is equipped with a forwardly extending lever 20 which may be depressed to effect rotation of the shaft whereby the trap door 17 is swung downwardly and a certain number of sugar lumps allowed to drop through the opening 16 into chute 6 and delivered thereby through opening 5 into the catch basin 7. When pressure is removed from the actuating lever 20, the parts are returned to normal position by the tension of a coiled spring 22 that is attached at its lower end to a bracket 23 fixed within the casing near the base and attached at its other end to the inner end of one of the plates 18. A stop 24 is extended inwardly from the bracket 23 which is adapted to be engaged by the plate 18 to which the spring is attached to serve as a means for limiting movement in this direction and to position the door 17 within opening 16.

Besides the two vertical plates 18—which support the door 17, there is a plurality of other vertically disposed plates 18 fixed 110

in spaced relation to shaft 19 and all these plates operate through slots 26 formed in the base plate 15. These plates are of rocker form and when the shaft 19 is in position at which the door 17 is closed, the ends of the plates at the lower side of plate 15 extend upwardly into the casing as does the plate 18 shown in Figure 2, but when the lever 20 is depressed, these plates are rotated with shaft 19 to swing their other ends upwardly to throw the sugar toward the discharge opening 16. At opposite side edges of the door 17 are vertically upstanding wings, or flanges, 30—31 which prevent too many lumps of sugar from rolling into the opening from the sides. One of these wings extends to a greater height than the other, as is indicated by the dotted lines 31 in Figure 2, to prevent lumps from wedging 20 between their upper ends.

Assuming the device to be so constructed, it is used as follows:

The upper part of the container is filled with cube sugar by removing the top cover 25 9. Then when it is desired to serve or dispense some of the sugar, the lever 20 is pressed downwardly. This causes shaft 19 to be rotated and door 17 to be swung downward from opening 16 in the inclined plate 30 15 and a plurality of lumps of sugar to be discharged into chute 6 and then into basin 7. When the lever 20 is released, the spring 22 returns the parts to normal position. As 35 a rule two or three lumps of sugar are delivered with each operation of the lever. If this should be too many, what is not used may be placed back in the container through the opening 10.

The device is intended to be made absolutely tight and fly-proof so that it will keep the sugar in a clean and sanitary condition.

Having thus described my invention, what I claim as new therein and desire to secure by Letters Patent, is:

45 1. In a device for serving lump sugar or

the like, a casing having a discharge opening, an inclined base plate in the casing provided with an opening communicating with the opening of the casing and having slots therein, a shaft extended revolvably through the casing below the base plate, a plurality of plates fixed to the shaft, a door supported by said plates for closing the opening of the base plate, yieldable means normally retaining the door in closed position and means at the outer end of the shaft whereby it may be rotated to move the door to open position and whereby said plates will be swung upwardly through the slots of the base plate to move the sugar toward the 60 discharge opening.

2. A device for serving lump sugar, or the like, comprising a base formed with a catch basin, a casing mounted on the base for containing the sugar and having a discharge opening adjacent the catch basin, an inclined plate fixed in the casing for supporting the sugar provided with an opening at its lower edge and having a plurality of parallel slots formed therein, a chute for receiving sugar from the plate opening and for delivering it through the casing opening into the catch basin, a shaft extending revolvably through the casing below the inclined plate, a plurality of vertically disposed plates fixed 70 to the shaft within the casing and extending through the slots in the inclined plate, a door supported by some of said plates to close the opening in the inclined plate, a spring attached to one of the plates and to the casing for normally retaining the door in closed position, a lever fixed to the outer end of the shaft whereby it may be rotated to move the door to open position; said plates that are fixed on the shaft being 75 adapted to swing upwardly into the casing when the door is opened to actuate the sugar toward the discharge opening.

MYRON E. KENNEY.
